UNITED STATES PATENT OFFICE.

WILLIS K. HODGMAN, OF TAUNTON, MASSACHUSETTS, ASSIGNOR TO HUBER-HODGMAN PRINTING PRESS CO., OF TAUNTON, MASSACHUSETTS, A CORPORATION OF MASSACHUSETTS.

INKING APPARATUS FOR PRINTING-PRESSES.

1,030,403.

Specification of Letters Patent. Patented June 25, 1912.

Application filed February 1, 1911. Serial No. 606,020.

To all whom it may concern:

Be it known that I, WILLIAM K. HODGMAN, a citizen of the United States, residing at Taunton, in the county of Bristol and 5 State of Massachusetts, have invented a new and useful Inking Apparatus for Printing-Presses, of which the following is a specification.

My invention relates to improvements in 10 inking mechanism for printing presses in which an ink table mounted on a reciprocating bed operates in conjunction with ink rollers to distribute the ink which is supplied to them from an ink fountain by 15 means of a ductor roller; and the objects of my invention are,—first, to provide for all of the composition ink rollers to be alike and interchangeable; second, to provide a light metal ductor roller of suitable 20 diameter to distribute the ink rapidly and to be easily started, rotated and stopped by contacting with the composition ink rollers; third, to so arrange the parts that the ink fountain is always open and accessible and 25 never obstructed by the ink table; fourth, to so arrange the parts that the ink table never passes through the path of the ductor roller; fifth, to provide a composition ink feed 30 roller which is always in contact with the fountain roller and with which the ductor roller 4 before the fresh ink being trans- 35 supply of ink; sixth, to so arrange the parts that the ink is delivered to a group of distributing rollers where it is distributed be- 40 fore it reaches the ink table. I attain these objects by the mechanism illustrated in the accompanying drawings, in which—

Figure 1 is a side elevation partly in section of an inking apparatus embodying my 45 invention, indicating the relation of the several parts in dotted lines. Fig. 2 is a top plan view of Fig. 1, partly broken. Fig. 3 is a vertical section on line $x-x$, Fig. 2.

Similar numbers refer to similar parts 45 throughout the several views.

In the drawings, 1 designates the ink fountain roll, located substantially in the path of but beyond the reach of the ink table; 2, the composition ink feed roller 50 which is always in contact with the fountain roller 1; and 3, the ductor roller which is

adapted to transfer the ink from the roller 2 to the composition ink table roller 4.

The three composition ink table rollers 5 are identical in construction and purpose 55 with the ink table roller 4, excepting that they do not receive ink direct from the ductor roller 3. These four ink table or distributing rollers are mounted in the usual way to contact with and distribute ink on 60 the ink table 6 and they contact in the usual way with the usual vibrating rollers 7 which continuously drive them to conform to the direction and speed of the ink table. The vibrating rollers 7 are driven by the usual 65 spur gears 8, 9, 10, 11 and 12, as plainly indicated in the drawings, the gear 12 receiving motion from the rack 13 which is reciprocated by the bed of the press in any well known manner, not shown. The vibrating 70 rollers 7 are vibrated in the usual manner by means of the vibrating arm 36 as plainly shown in Fig. 2. The fountain segment 14 is oscillated to and fro by the crank pin 15, on the spur gear 16, through the medium of 75 the connecting rod 17, and pin 18, in the fountain segment. The gear 16 is continuously rotated in the direction of the arrow by mechanism, not shown, and makes one turn to each complete stroke of the press. 80 The fountain segment meshes with and oscillates the segment 19 which is mounted loosely beside the fountain ratchet wheel on the outer end of the fountain roller 1. The segment 19 carries the usual fountain pawl 85 20 which operates to turn the fountain roller step by step by engaging the teeth of the fountain ratchet wheel 21 which is fast to the outer end of the fountain roller. The fountain pawl 20 is controlled by a drag, 90 not shown, which can be adjusted to allow the fountain roller to receive a turn equal to the full stroke of the fountain segment 14 down to one tooth of the ratchet wheel 21 or even nothing at all. The ductor roller 3 is 95 mounted upon oscillating levers 22 which are attached to a rock shaft 23 journaled in the frame of the machine, and provided with an arm 24, carrying a pin 25, connecting the end of the connecting rod 26. The 100 other end of the connecting rod 26 passes through the free end of the lever 27 and is

positioned relative to sliding movement through the lever by springs 28 which are interposed between the free end of the lever and collars 29 which are fast on the connecting rod 26. The lever 27 is fulcrumed on the stud 30 in the frame of the machine and its free end receives an oscillating movement by means of the cam groove 31 and the cam roller 32 which is carried by the pin 33, in 5 10 15 20 25 30 35 40 45 50 55 60 65 70 75 80 85 90 95 100 105 110 115 120 125 130

the lever 27. The adjusting bolts 34 tapped through the lugs 35 provide means for regulating the ductor roller 3 to contact with the composition rollers 4 and 2 with the desired pressure, the springs 28 yielding more or less in accordance with the throw of the arm 24 as permitted by the adjusting bolts 34.

In the drawings the ink table 6 has reached its nearest approach to the ink fountain and the ductor 3 has just contacted with 20 the distributing roller 4. Now on account of the distance from the contacting point of the distributing roller 4 with the ink table being farther away from its contacting point with the ductor 3 than to the end of the ink 25 table, none of the fresh ink from the ductor roller can reach the ink table during its stroke away from the ink fountain until it has been thoroughly distributed by the group of rollers, 5, 7 and 4, because the ink 30 table passes from beneath the distributing roller 4 before the fresh ink being transferred to the roller from the ductor can reach it. The ductor remains in contact with distributing roller 4 during substantially 35 the whole of the stroke of the ink table away from the ink fountain and at the beginning of the return stroke it moves to contact with the composition roller 2 and stays in contact with that roller during the major 40 45 50 55 60 65 70 75 80 85 90 95 100 105 110 115 120 125 130

part of the return stroke to receive a new supply of ink.

Operation: When the fountain roller 1 is rotated, the ink is taken from it by the feed roller 2 and fed to the ductor roller 3 which transfers it to the distributing roller 4 from which it is taken and thoroughly distributed by the first group of distributing rollers 5, 7 and 4, before it is distributed upon the ink table 6. From the ink table 50 the ink is transferred to the second group of distributing rollers and to the form rollers and form, not shown, in the usual manner.

What I claim is:

55 1. In an inking apparatus for a bed and cylinder printing press, the combination of a reciprocating bed and ink table, a group of continuously contacting ink table rollers and vibrating rollers, means for continuously 60 driving said group of rollers to conform to the direction and speed of said reciprocating bed and ink table, means for vibrating said vibrating rollers endwise, a fountain roller, a feed roller continuously contacting with 65 said fountain roller, and a ductor roller al-

ternately contacting with said feed roller and one of said ink table rollers.

2. In an inking apparatus for a bed and cylinder printing press, the combination of the following instrumentalities, a reciprocating bed and ink table, a group of continuously contacting ink table rollers and vibrating rollers, means for continuously driving said group of rollers to conform to the direction and speed of said reciprocating bed and ink table, means for vibrating said vibrating rollers endwise, a fountain roller, a feed roller continuously contacting with said fountain roller, and a ductor roller alternately contacting with said feed roller and one of said ink table rollers; said instrumentalities so located and timed in relation to each other that each fresh supply of ink is fed to said group of rollers by said ductor roller during a part of the departing and returning strokes of said bed and ink table and distributed upon said group of rollers only until said ink table contacts with said ink table rollers on its returning stroke. 90

3. In an inking apparatus for a bed and cylinder printing press, the combination of an ink table carried by the reciprocating bed, a fountain roller located substantially in the path of but beyond the reach of the ink table, a feed roller continuously contacting with said fountain roller, an ink table distributing roller and a ductor roller mounted and actuated to alternately contact with the feed roller and with the ink table distributing roller. 95

4. In an inking apparatus for a bed and cylinder printing press, the combination of a reciprocating bed and ink table, an ink fountain located substantially in the path of but beyond the reach of said ink table, an ink fountain roller, an ink table distributing roller, a feed roller continuously contacting with said ink fountain roller, and a ductor roller mounted and actuated to alternately contact with said feed and said ink table distributing rollers, with means to actuate said ductor roller to make and break contact with said ink table distributing roller at times when said reciprocating bed is practically on dead centers and said ink table distributing roller practically at rest. 110 115

5. In an inking apparatus for a bed and cylinder printing press, the combination of a reciprocating bed and ink table, an ink fountain located substantially in the path of but beyond the reach of said ink table, an ink fountain roller, a feed roller continuously contacting with said ink fountain roller, an ink table distributing roller, a ductor roller mounted to alternately contact with said feed roller and said ink table distributing roller, and means to actuate the said ductor roller to make and break contact with said ink table distributing 120 125 130

roller when said reciprocating bed is practically on dead centers and said ink table distributing roller practically at rest, the location of the several rollers being such that the distance around the said ink table distributing roller from said ductor roller to said reciprocating ink table is greater

than the length of said reciprocating ink table inked by said ink table distributing roller.
